OPEN CUTTING DIE FOR MAKING SHOE PARTS

Fred J. Halloran, 21 Salem St., Swampscott, Mass.

Filed Sept. 26, 1961, Ser. No. 66,860

Term of patent 14 years

(Cl. D54—4)

FIG. 1

FIG. 2

FIG. 3

FIG. 4

FIG. 1 is a view in perspective of an open cutting die for making shoe parts showing my new design. The sides not shown are the same in appearance as the respective sides shown,

FIG. 2 is a view of the die in side elevation on a reduced scale,

FIG. 3 is a plan view of the die on the same reduced scale,

FIG. 4 is a fragmentary view of a die of alternative design in which the conical bumpers are mounted inside the contour of the die instead of outside its contour as shown in FIGS. 1-3.

The characteristic features of my new design for open cutting die for making shoe parts reside in the shapes and location of the three bumpers, which are each comprised of a central flange and two cones and are mounted on the walls of the die, and the circumferentially disposed

areas lined to represent orange color, as best shown in FIGS. 1 and 5.

I claim:

The ornamental design for an open cutting die for making shoe parts, substantially as shown and described.
